UNITED STATES PATENT OFFICE.

CHARLES F. KLEIN AND WILLIAM H. WOODARD, OF CLEVELAND, OHIO.

PORTABLE OVEN.

SPECIFICATION forming part of Letters Patent No. 249,843, dated November 22, 1881.

Application filed June 18, 1881. (No model.)

To all whom it may concern:

Be it known that we, CHARLES F. KLEIN and WILLIAM H. WOODARD, of Cleveland, in the county of Cuyahoga and State of Ohio, have invented new and useful Improvements 55 in Portable Ovens, of which the following is a description.

Our invention in ovens relates to a peculiar device for connecting the top, bottom, and 10 sides of the oven to each other, so that said several parts can be readily put together and taken apart, as may be desired; also, to certain other improvements in said ovens, herein- 15 after fully set forth and claimed, and illustrated in the annexed drawings, making a part of this specification, in which—

Figure 1 is a front view of the oven. Fig. 2 is a side view. Fig. 3 is a horizontal transverse section. Fig. 4 is a vertical transverse 20 section. Figs. 5 and 6 are detached sections.

Like letters of reference refer to like parts in the several views.

The several sides of the oven are joined to each other as follows: The vertical edges of 25 the two sides A and B, Fig. 3, are so bent as to form a groove along each edge, as seen at C C.

It will be observed that the metal is bent 30 inward to form said grooves, thereby forming a shoulder, *a*, on one side of the groove. The purpose of said shoulder will presently be shown. The upper and bottom edges of the sides are bent inward at right angles, forming flanges *b* and *c*, respectively, along the inner 35 edges of said sides, as seen in Figs. 3, 4, and 5. The two sides D and E, Fig. 3, have each of their vertical edges turned inward at right angle, forming flanges F and G, Fig. 3. Said 40 figure represents a horizontal transverse section, and in which it will be seen that the flanges are adapted to fit in the grooves C of the sides A and B, thereby locking the four sides of the oven firmly together at the corners, substantially as shown in Fig. 3. The 45 two sides D and E are prevented from being pushed inwardly by the returns or flanges F G impinging upon the shoulders *a* of the grooves C, and at the same time they are prevented from being forced outward by the said returns 50 or flanges bearing against the outer sides of

the grooves—that is to say, the flanges of the sides D and E—for, being held in the grooves C of the sides A and B, the sides of said grooves serve as shoulders on either side of the flanges, which prevents the sides D E of the oven from 55 being pushed inward or outward. The sides A B are prevented from being forced inward or outward by means hereinafter described.

The top of the oven is secured to the sides as follows: As seen in the drawings, H represents the top of the oven. The edges of its four sides are turned down at right angles, forming a flange, I, on each of the four sides, as seen in the drawings. The central portion of the top is depressed, leaving a narrow ridge 60 or rim around the edge of the top, as seen at e, Figs. 4 and 6. Said rim covers the edges of the sides, while the flanges I of the top lap down over the sides externally. The depressed central part of the top fits down in between the 65 four sides and forms a shoulder for each side, against which the inturned edges *b* of said sides abut, as seen in Fig. 4, thereby preventing the sides A and B of the oven from being 70 pressed inward, but which cannot be forced 75 outward, as they are locked in the return or flange C of the sides D and E, substantially as shown in Figs. 3 and 4.

The top of the oven is secured in place by a slide, J, Fig. 5. Said figure represents a portion of the under side of the top of the oven and parts of two sides, in order to show the application of the slide for the purpose specified. Said slide consists of a piece of sheet metal having therein slots 1 and 2, in which 80 are rivets, whereby the slides are made fast to the under side of the top, not so tight but that the slides can be moved.

In order to put on the top, the slides are drawn inward, so that they may be out of the 85 way of the flanges *b* of the sides. The top is put on so that the flanges I thereof will lap down upon the sides of the oven. The slides J are then forced outward and under the flanges *b* of the sides, as shown in Figs. 4 and 6, thus 90 firmly uniting the top to the sides of the oven, but which can be easily removed therefrom when the slides are drawn back.

The bottom C' of the oven may be secured 95 to the sides thereof substantially in the same 100

way as is the top; or for that purpose straps or ears K, of sheet metal, may be used. (See Figs. 3 and 4.) One end of the ears is soldered or otherwise secured to the bottom of the oven, 5 one on each opposite side, and so far in from the sides of the oven as to touch or be at the edge of the flange c, against which the edges of said flange abut. The flanges thus abutting against the ears prevent the lower ends of the 10 sides from being pushed inward, as the shoulders of the depressed top prevent the upper ends of the sides from being pushed inward.

The upper ends of the ears above alluded to are bent over against the sides of the oven and 15 secured thereto by a screw-bolt, i, thereby securely connecting the bottom to the sides of the oven, as seen in Fig. 4.

From the above description it will be obvious that the sides, top, and bottom of the oven are 20 all put together without soldering; hence when the several parts of the oven are put together they can be readily taken apart and the several pieces piled one upon the other, forming a small package as compared with the pieces 25 when put together forming an oven, thereby reducing the expense of shipping the article from first-class freight to the third or fourth class, also making the ovens more convenient to handle and less liable to be bruised in trans- 30 portation.

L, Figs. 3 and 4, is a damper or spreader covering the hole M in the bottom of the oven. To the top of the damper or spreader is secured a bar, N, in each end of which is fixed the lower 35 end of a rod, O, extending upward therefrom in the corners of the oven and through the top. The projecting ends above the top are threaded and provided with a nut, P, whereby the rods may be screwed upward or downward for open- 40 ing and closing the damper for the admission of more or less heat into the oven from the burner.

In the door A' of the oven is a plate of glass, B', through which may be seen and watched 45 the contents of the oven while cooking without opening the door for that purpose or admitting to the oven an inflow of cold air. R,

Fig. 4, is an inner top of the oven, forming with the outer one, H, an air-chamber, c'. By means of the air-chamber the heat is retained 50 in the oven above the cooking food a longer time and in greater degree, so that the baking is more uniformly done than when the oven is without such a chamber.

The spreader above alluded to in this class 55 of stoves is ordinarily a fixture. Therefore it is incapable of regulating the amount of heat admitted to the oven. Its ordinary use is not to regulate the heat, but to spread it from the center to the sides of the oven. Our adjustable spreader 60 becomes a means of regulating the heat in the oven, and at the same time serves the purpose of a spreader as well as one that is stationary. Furthermore, by having the spreader adjustable it can be readily adapted to either an oil 65 or gasoline stove, for the distance that the spreader should be above the opening in an oven for a gasoline-stove will not be suitable for an oil-burning one, owing to the different positions of the flames in the two stoves. 70

What we claim as our invention, and desire to secure by Letters Patent, is—

1. In combination with the sides of the oven and top thereof, a slotted side, J, attached to the said top and adapted to slide under the 75 inward-projecting flanges b of the sides, substantially as set forth, and for the purpose specified.

2. The combination of the top, bottom, and sides of the herein-described oven, the several 80 parts constructed and joined to each other as set forth, air-chamber c', and an adjustable spreader operated by adjusting screw rods and nuts, all constructed and arranged in the manner substantially as set forth, and for the pur- 85 poses specified.

In testimony whereof we affix our signatures in presence of two witnesses.

CHARLES F. KLEIN.
WILLIAM H. WOODARD.
